UNITED STATES PATENT OFFICE.

AXEL A. LEANDER, OF SEATTLE, WASHINGTON.

GARMENT.

Application filed January 9, 1922. Serial No. 528,004.

To all whom it may concern:

Be it known that I, AXEL A. LEANDER, a citizen of the United States, and a resident of the city of Seattle, county of King, State 5 of Washington, have invented certain new and useful Improvements in Garments, of which the following is a specification.

This invention relates to improvements in garments, and more particularly to detachable cuffs for trousers; the principal object 10 of the invention being to prolong the life of such garments by equipping the same with cuffs which, after becoming worn, may be removed without any damage to the garment itself, and if desired may be replaced by new cuffs.

A further object is to provide removable, or detachable, cuffs which will add to the appearance of the garment and which will 20 protect the bottom edges of the legs of the trousers and prevent them from being worn out before the rest of the garment.

Other objects of the invention reside in the manner of forming the cuff and of attaching it to the garment.

In accomplishing these and other objects of the invention, I have provided the improved details of construction, the preferred forms of which are illustrated in the accompanying drawings, wherein—

Figure 1 is a view of a pair of trousers showing one of the legs thereof equipped with a cuff, and a cuff ready to be applied to the other leg.

Figure 2 is a view illustrating the first step in attaching a cuff.

Figure 3 illustrates a step following that shown in Figure 2.

Figure 4 is a perspective view of a portion of the leg of a pair of trousers showing the cuff attached.

Referring more in detail to the several views of the drawings, wherein like reference numerals designate the same or like parts—

1 designates, as a whole, a pair of trousers having legs 2 to which cuffs, as designated at 3, are applied.

Before the cuff is applied, the trousers are 50 finished about the bottom edges, so that after a cuff has become worn and is removed, the trousers will not have to be altered or finished in any way.

The cuff, before being applied, is formed

from a strip of cloth of desirable width and 55 length, into a sort of sleeve, as shown at 4 in Figure 1, and this is turned wrong side out and slipped over the lower portion of the leg of the trousers, as shown in Figure 2 and is then fastened about its lower edge 60 by stitching, as is indicated at 5, to the lower edge of the leg.

After the lower edge of the cuff has been fastened, the upper edge is folded back over the lower portion so that it extends 65 below the edge of the trousers, as is shown in Figure 3, and is then turned upwardly on the inside of the trousers and is fastened at its edge to the trousers by whipped stitching, as shown at 6 in Figure 4. 70

It is apparent that with the cuff so attached to the trouser leg, by properly folding the cuff forming material, the apparent length of the leg may be made longer or shorter, while the width of cuff remains the 75 same. After the cuff strip has been applied and attached and folded to give the proper length to the leg, the cuff may be pressed and will then retain its shape.

With the cuff so attached, it will be noted 80 that the lower edges of the trousers are protected, and that after the cuff has become worn, it may be removed by cutting out the stitching 6 and then the stitches 5.

Cuffs of this character may be made in 85 desired widths and would be made of the same cloth as the trousers so that, when applied, they would give the latter a finished appearance while, at the same time, they will add to the life of the garment. 90

Having thus described my invention, what I claim as new therein and desire to secure by Letters-Patent, is:

A trouser leg having a finished end and a cuff detachably secured about said finished end, comprising an up-turned inner portion that is whip stitched to the interior of the leg and an outer portion forming the visible cuff having a downwardly and inwardly turned end that is stitched about its edge to 100 the trouser leg, thereby permitting the cuff to be adjusted in such manner as to add to or shorten the apparent length of the trouser leg.

Signed at Seattle, Washington, this 3rd 105 day of January, 1922.

AXEL A. LEANDER.
